METHOD AND APPARATUS FOR CASTING

William C. Brown, Cambridge, Mass.

Application June 13, 1940, Serial No. 340,299

9 Claims. (CL 22—203)

The present invention relates to electrical equipment and methods and apparatus for assembling the same, and is more particularly concerned with the formation of electrical connections in complicated assemblies, such as radio receivers.

According to usual methods of manufacturing radio receivers the larger parts, such as audio-frequency transformers, intermediate-frequency coils, variable condensers, tube sockets and the like, are mounted on a chassis. The necessary electrical connections are then made by soldering wires to suitable lugs on these parts. This method of assembly is not only expensive but, since it is done by hand under high-speed conditions, frequently gives rise to poor joints and misplaced connections. Furthermore, due to the random placing of the connections, stray capacitances and mutual inductances will vary from set to set, thus requiring final adjustments in an effort to obtain uniformity of performance.

The object of the present invention is primarily to avoid the disadvantages above noted, with a view to reducing the cost of manufacture and improving the uniformity of performance and operation.

With this and other objects in view as will hereinafter appear, the present invention comprises electrical equipment and the method and apparatus for its assembly hereinafter described and particularly defined in the claims.

In accompanying drawings Fig. 1 is a simplified isometric view of a chassis of a radio receiver in which the wiring assembly is to be formed according to the present invention; Fig. 2 is a view of the solder bath; Fig. 3 is a view of the chassis with the wiring assembly completed; Fig. 4 is a view of the mold base and associated parts; Fig. 5 is a detail view of a jig for bending connections; Figs. 6, 7 and 8 are detail views illustrating the formation of wiring connections at two levels; and Figs. 9 to 12 are detail views illustrating a modified and preferred method of forming wiring connections at two levels.

The invention will now be specifically described as embodied in a method and apparatus for forming certain electrical connections between parts of a radio receiver. In Fig. 1 there is illustrated a chassis 10 on which are mounted two tube sockets 12 and 14, each with downwardly extending lugs 16 to which electrical connections are to be made. It will be understood that the usual chassis base will also include other pieces of equipment, such as audio- and intermediate-frequency transformers as well as a greater num-

ber of tube sockets, all such equipment having connecting lugs similar to the lug 16. The principles of the invention are, however, applicable to any wiring assembly regardless of its complexity, and for reasons of convenience it will be assumed that in this specific instance connections are to be established only between the lugs of tube sockets 12 and 14, together with the introduction of certain small component parts which are to be presently described.

In Fig. 3 is shown the assembly as it appears when completed (the chassis being here inverted with respect to Fig. 1). The assembly involves various connections between the lugs of the tube sockets, as well as the connection and support of two small component parts 18 and 20. In general, these component parts comprise small elements such as resistors and fixed condensers which do not need to be mounted on the chassis and are supported in the finished assembly by the connections themselves. These parts are here shown as fixed resistors.

The connections are formed by immersing the lugs 16 into a soldering pot 22 (Fig. 2), in which 25 a mold base is also immersed. The mold base 24, as shown in Fig. 4, comprises a plate formed with openings 26 to permit drainage of molten solder. Mounted on the base are a number of 30 molding troughs indicated at 28, 30, 32, 34 and 36 of such lengths and configurations as to provide the desired wiring layout for the assembly. Preferably each mold comprises a piece of stock of the proper shape from which a trough has been milled or otherwise formed in its upper 35 surface.

Also mounted on the mold base 24 are two supporting pans 38 and 40 to hold the parts 18 and 20 during the molding operation. Each pan comprises a piece of stock suitably hollowed in 40 its upper surface to form an accurate positioning means for the part which is to be retained.

The several trough molds and supporting pans, as well as the base 24, are constructed of stock, preferably aluminum, which is not wet by the 45 solder alloy, so that upon removal of the entire mold from the solder pot, the solder will run off without sticking to any of these parts. The trough molds 28 to 36 are of such a height that they are submerged in the bath and the supports 50 38 and 40 are of sufficient height to extend slightly above the level of the bath.

Prior to immersion of the mold, the resistors 18 and 20 are placed in the pans 38 and 40. The leads at the ends of the resistors may be bent in a preceding operation so that their ends

will properly enter the desired molding trough, as is illustrated for the part 18. Or, alternatively, the leads may be initially straight, subject to a bending operation after the resistor is mounted in the supporting pan. This latter procedure is illustrated for the resistor 20. After placing the resistor 20 in the pan 40, a bending jig 42, shown in Fig. 5, is brought down over the mold assembly in proper register therewith. The jig is provided with downwardly extending notched plates 44 which are positioned to engage the protruding leads and bend them downwardly into their respective molding troughs. As shown in Fig. 4 the leads at the end of the resistor 20 have been thus bent down by the action of the bending jig.

The chassis 10 is then registered with the mold base, and the entire mold is immersed in the solder pot. Rods 43 at the corners of the mold base serve not only to register the parts, but also as convenient grips to assist in lowering the mold and chassis into the solder pot. If desired, the mold base may be immersed first and the chassis may afterwards be placed over it. In either case the troughs (28 to 36) are completely submerged while the resistors 18 and 20 are supported out of the bath. Preferably the parts are so arranged that the ends of the chassis abut the rods 48, and the aprons 49 of the chassis fit over the sides of the solder pot.

It has been found in some instances that the solder does not flow readily into the molding troughs on immersion, but the flow may be enhanced by imparting a vibration to the mold, preferably by applying a vibrating hammer of any suitable type to one of the rods 48. Alternatively, the filling of the troughs may be accomplished by removing and re-submerging the mold once or twice, with or without some vibration, but the method of relying on vigorous vibration only is considered preferable because it is more rapid and affords less time for damage to the resistors due to heating. As soon as the troughs are filled, the chassis base and the mold assembly are lifted bodily from the bath by the rods 48. The excess solder runs back into the bath through the holes 26 and only the proper amount of solder remains in the troughs to form the desired connections. Preferably the vibration is continued during the removal of the mold from the bath, in order to insure proper flow of the solder around the various connections.

The parts are then subjected to forced cooling, conveniently by a fan, not only for the purpose of rapidly hardening the solder but also to prevent overheating of the resistors 18 and 20. The chassis base can then be easily freed from the mold since the solder does not stick to the aluminum mold parts. With molding troughs of the shape shown in Fig. 4 the connections illustrated in Fig. 3 will be formed.

It will be understood that the connections of Fig. 3 are illustrative only, and that connections may be formed according to any desired arrangement.

In electrical apparatus of considerable complexity it is frequently necessary to form the connections in two or more levels because of the multitude of crossovers and the space requirements for parts. It will be understood that it is impossible in a single level to form solder connections which are to cross one another without electrical contact. For such complex as-

semblies, of which radio receivers may be taken as an example, the present invention provides for making connections at two levels. For this purpose two alternative procedures may be followed.

In Fig. 6, I have illustrated a tube socket 50 which is provided with special lugs 52, each of a type to permit multiple electrical connections at different levels. Each lug 52 comprises a connector 54 of the same length as one of the standard single lugs 16 of the socket previously described, and a longer connector 56, these parts being attached together by a web 58. For the connections at the first level the part 54 is introduced into its molding trough (indication at 60) exactly as heretofore described. After the formation of the first level connections, typified by the hardened solder bar 62, the whole assembly is immersed in another solder bath in which a different mold assembly has been submerged. This second mold assembly is similar to that previously described except for the different layout of connections, the molding troughs 64 thereof (Fig. 8) being designed to register with the long connectors 56. As shown in Fig. 20 25 25 25 30 30 30 35 35 35 40 40 40 45 45 45 50 50 50 55 55 55 60 60 60 65 65 65 70 70 70 75 75 75

It will be understood that certain electrical connections will be formed at one level only, for which purpose single connectors of the proper lengths may be used.

Another and preferred method of making multiple connections in more than one layer is shown in Figs. 9 to 12. As here shown the lugs used for multiple connections are of simple wire form but long enough to extend through both levels, as indicated at 66. For the first level molding, a trough 68 is used, having an opening through which the lug 66 passes. After the molding of the first level and the withdrawal of the mold and chassis from the bath, a certain amount of solder will cling to the bottom ends of the long lugs as indicated at 70 in Fig. 10. These ends are heated for the purpose of melting the solder which clings thereto. This heating is most easily carried out by re-immersion of such ends in solder, as indicated diagrammatically in Fig. 11, to only such depth and for such time as required to melt off the solder 70 without affecting the previously formed solder joints. The lugs 66 can then be withdrawn through the holes in the molding troughs 68 before any of the solder material has an opportunity to harden thereon. Thus the first level of connections is completed. The second level of connections is then formed by introducing the bottom ends of the lugs 66 into submerged molding troughs 72 which have been shaped in accordance with the desired second level layout (Fig. 12). This process may be repeated for any number of levels but it has been found that in electrical equipment typified by radio receivers the formation of two levels of connections is generally sufficient.

It will be understood that although a radio receiver has been taken as an example, the invention is equally applicable to electrical equipment of other types, and further, that although simplified connections are herein shown, the invention is applicable to assemblies of any degree of complexity. In other respects, also, the invention is not to be considered as limited to the precise embodiment herein described. For example, the

term "chassis" as herein used is meant to apply to a panel or base on which equipment is mounted, and the term "solder" applies to any molten material which is capable of hardening upon cooling to form the connections determined by the arrangement of the mold troughs.

Having thus described the invention, I claim:

1. A method of assembling and forming electrical connections for complex electrical apparatus which consists in taking a chassis having lugs thereon, immersing the lugs in register with mold troughs in a solder bath, said troughs being of a size to form long and narrow connections, supporting a component part out of contact with the solder, the component part having leads extending into mold troughs, removing the mold and chassis together from the bath, and separating the chassis with its formed connections from the mold after hardening of the solder.

2. A method of assembling and forming electrical connections for complex electrical apparatus which consists in taking a chassis having lugs thereon, immersing the lugs in register with mold troughs in a solder bath, said troughs being of a size to form long and narrow connections, said immersion being repeated to insure flow of solder into the troughs, removing the mold and chassis together from the bath, and separating the chassis with its formed connections from the mold after hardening of the solder.

3. A method of assembling and forming electrical connections for complex electrical apparatus which consists in taking a chassis having lugs thereon, immersing the lugs in register with mold troughs in a solder bath, said troughs being of a size to form long and narrow connections, removing the mold and chassis together from the bath, separating the chassis from the mold, immersing the lugs in a bath in conjunction with another mold to form connections at another level, removing the chassis and second mold from the bath, and separating the chassis from the second mold.

4. Apparatus for assembling and forming electrical connections for electrical equipment comprising a mold base having long and narrow troughs thereon, a solder pot to contain a bath in which the mold base is immersed, supports on the base to hold component parts out of contact with the solder, means for immersing soldering lugs on a chassis in register with the troughs, and means for removing the mold base and chassis together from the bath.

5. Apparatus for assembling and forming electrical connections for electrical equipment comprising a mold base having long and narrow troughs thereon, a solder pot to contain a bath in which the mold base is immersed, supports on the base to hold component parts out of contact with the solder, certain of the troughs being arranged to receive leads connected with said component parts, means for immersing soldering lugs on a chassis in register with the troughs, and means for removing the mold base and chassis together from the bath.
6. In apparatus for assembling and forming electrical connections for electrical equipment, a solder bath, a plurality of molds having long and narrow troughs to form connections at different levels, and means for registering connectors on pieces of electrical equipment with the troughs of each of the molds successively.
7. In apparatus for assembling and forming electrical connections for electrical equipment, said equipment having lugs with multiple connectors to form connections in different sets, a mold having troughs to register with one set of connectors, a second mold having troughs to register with another set of connectors, and solder bath means in which the lugs are immersed in successive register with the molds.
8. In apparatus for assembling and forming electrical connections for electrical equipment, a mold having long and narrow troughs to register with connectors on said equipment, including troughs having openings to permit passage of long connectors therethrough, a second mold having troughs to form connections at a different level and including troughs registering with the ends of said long connectors, and solder bath means in which the molds and the connectors are immersed.
9. A method of assembling and forming electrical connections for electrical equipment which consists in taking a chassis having connectors, immersing in a solder bath a mold to form electrical connections to said connectors, immersing the connectors in the bath in register with the mold and with connectors passing through the mold, removing the mold and chassis from the bath, heating the ends of the connectors to free them of the mold, and repeating the molding operation with a different mold to establish connections at the ends of the connectors.

WILLIAM C. BROWN.
